(57) **CLAIM**

The ornamental design for a stethoscope, as shown and described.

DESCRIPTION

FIG. 1 is a front perspective view of the stethoscope showing my new design;

FIG. 2 is a front perspective view thereof;

FIG. 3 is a rear perspective view thereof;

FIG. 4 is a right side view thereof; and,

FIG. 5 is a left side view thereof.

The broken line showing in FIG. 1 is for environmental purposes only and forms no part of the claimed design.
